LUBRICATING DEVICE FOR SEWING MACHINES

Walter Myers, Bridgeport, Conn., assignor to The Singer Manufacturing Company, Elizabeth, N. J., a corporation of New Jersey

Application December 6, 1938, Serial No. 244,145

12 Claims. (CL. 112—256)

This invention relates to sewing machines and has for its primary object to provide improved means for properly lubricating the thread-case raceway of a sewing machine loop-taker to meet requirements at different speeds of operation of the sewing machine.

A further object of the invention is to provide the work-arm class of sewing machine with lubricating means for work-feeding and loop-taker actuating mechanisms constructed and arranged within the work-arm to safeguard the work and stitching threads from becoming soiled by lubricant.

The invention consists in the devices, combinations and arrangements of parts hereinafter described in connection with the accompanying drawings which illustrate a preferred embodiment of the invention and in which:

Fig. 1 represents a top plan view of the work-arm of a feed-off-arm sewing machine having the work-arm cover-plate removed. Fig. 2 represents a vertical section longitudinally of the work-arm with its cover-plate applied thereto, the section being taken substantially on the line 2—2 of Fig. 1. Fig. 3 represents an enlarged transverse section of the work-arm on substantially the line 3—3 of Fig. 1, with the addition of the work-arm cover-plate. Fig. 4 represents an enlarged cross-section of a portion of the work-arm adjacent the carrier-arm therefor, the section being taken on substantially the line 4—4 of Fig. 1 and including the work-arm cover-plate. Fig. 5 represents an enlarged detail view, partly in perspective and partly in section, of the loop-taker shaft bearing-bracket and the oil-metering device therein. Fig. 6 represents a vertical section of the portion of the work-arm partition-wall containing the oil-trap, the section being taken longitudinally of the work-arm.

The present invention has been embodied in a feed-off-arm zigzag stitching machine of which the frame corresponds, in general, to that disclosed in my prior U. S. Patent No. 1,999,973, April 30, 1935. As illustrated in the present drawings, the frame referred to includes a horizontally disposed carrier-arm 1 from which extends a hollow or trough-shaped work-arm 2 free at its end opposite to the carrier-arm 1.

Journalized in ball-bearings 3 and 4 in the carrier-arm 1 and work-arm 2 is a rotary actuating shaft 5 extending crosswise of the length of the work-arm 2, upon which shaft is suitably secured the hub 6 of a bevel-gear 7. In mesh with the bevel-gear 7 is a smaller bevel-gear 8 secured upon one end of a shaft-section 9 of a seq-

tional loop-taker actuating shaft extending lengthwise of the work-arm, the gears 7 and 8 being proportioned so that the shaft-section 9 rotates twice for each rotation of the actuating shaft 5. The shaft-section 9 is rotatably journaled in a bushing 10 fixed in a suitably apertured bearing-block 11 secured by screws, as 12, upon a lug 13 rising from the bottom wall of the work-arm 2 at the carrier-arm end thereof.

At its end opposite the bevel-gear 8, the shaft-section 9 has a suitably socketed head 14 connected by a universal joint with one end of a shaft-link 15, of which the opposite end is similarly connected with a socketed head 16 carried by a reduced end of a loop-taker carrying shaft-section 17. The shaft-section 17 is rotatably journaled in a bushing 18 secured, by a screw 19, for endwise adjustment in a suitably apertured work-arm partition-wall 20, one end of said bushing abutting the shaft-section head 16.

Secured upon the end of the shaft-section 17, to abut the other end of the bushing 18, is the hub 21 of a horizontal-axis loop-taker 22 of the rotary-hook type. The loop-taker 22 has a cup-shaped body internally provided with the usual annular raceway, in which raceway is journaled the bearing-rib of a thread-case carrier 23, as disclosed in the U. S. patent to G. A. Fleckenstein et al., No. 2,103,899, Dec. 28, 1937. The thread-case carrier 23 is restrained against rotation with the loop-taker by a bent arm 24 secured upon a side wall of the work-arm 2. The loop-taker 22 cooperates with a vertically reciprocatory and laterally vibratory needle 25 in the formation of zigzag lock-stitches, said needle operating through a slotted work-supporting throat-plate 26 and being actuated in any usual or suitable manner so that successive work-penetrating movements thereof are performed in separate paths spaced transversely of the length of the work-arm 2.

It will be noted that by endwise adjustment of the bushing 18 in the partition-wall 20, the loop-taker 22 may be conveniently set for proper cooperation with the needle 25, without disconnecting the loop-taker actuating connections, the universal-joint connections between the shaft-sections permitting of the requisite movement of the bushing 18. It will further be noted from Fig. 2 of the drawings that the rotation axis of the loop-taker shaft-section 17 is higher than that of the shaft-section 9, whereby the work-arm 2 may be tapered toward its free end so as to be of minimum cross-section at the stitching point.

The throat-plate 26 is suitably secured upon the work-arm in abutting relation with a work-arm cover-plate 27 secured by screws, as 28, upon the upper edges of the work-arm, a gasket 29 being preferably interposed between said work-arm and the cover-plate and throat-plate to provide an oil-tight joint therebetween. The partition-wall 20 rises from the bottom wall of the work-arm adjacent the free end thereof and extends entirely across the work-arm widthwise thereof, the upper face of said partition wall being substantially flush with the upper side edges of the work-arm, whereby the gasket 29 seals said upper face of the partition-wall 20. It will therefore be understood that the partition-wall 20 divides the hollow work-arm into an oil-splash actuating mechanism containing compartment and a sewing-mechanism containing compartment.

The work is advanced lengthwise of and toward the free end of the work-arm 2 by a feed-dog 30 which operates through suitable slots in the throat-plate 26 and is opposed by a presser-foot 31. The feed-dog 30 overhangs the loop-taker 22 at the free end of the work-arm 2 and is secured by screws 32 upon one end of a feed-bar 33. The feed-bar 33 extends lengthwise of and within the work-arm 2 adjacent one side wall thereof, said feed-bar being slidably guided by the walls of a slot 34 in the partition-wall 20. The feed-bar 33 is supported for rocking and endwise sliding movements within an upwardly open guide-slot 35 provided in an extension 20' of the partition-wall 20, said feed-bar having an elongated aperture 36 to slidably receive a pivot-block 36' upon the eccentric end of an adjustable fulcrum-pin 37 secured, in set position in the wall-extension 20', by a screw 38. The set-screw 38 is preferably accessible from the top of the work-arm by the provision of a suitable aperture in the work-arm cover-plate 27 and its underlying gasket 29, said gasket by its engagement with the top face of the partition-wall extension 20' serving to prevent oil-leakage through said apertures. The fulcrum-pin 37 extends horizontally across the work-arm 2 and through a bearing-boss 39 in the work-arm side wall opposite to the feed-bar side wall, so as to be conveniently accessible for adjustment.

At its end opposite to the feed-dog 30, the feed-bar 33 has a laterally offset fork 40 embracing a feed-lift eccentric 41 carried by the rotary shaft 5, said eccentric imparting rocking movements to said feed-bar about the fulcrum-pin 37, and thereby rising and falling movements to the feed-dog 30. Adjacent the eccentric 41, the shaft 5 carries an adjustable feed-advance eccentric 42 which is constructed and may be adjusted substantially in accordance with the disclosure in my prior U. S. Patent No. 2,053,968, Sept. 8, 1936. The feed-advance eccentric 42 is embraced by a fork 43 which is transverse to the fork 40 and forms one end of an arm 44 of which the other end is adjustably secured by screws 45 upon the feed-bar 33. It will be understood that the feed-advance eccentric 42 imparts endwise reciprocatory movements to the feed-bar 33 and therefore work-advancing and return movements to the feed-dog 30.

The present invention relates to means for automatically lubricating the actuating mechanism above described and, more particularly, for lubricating the thread-case raceway in the loop-taker. As illustrated in Fig. 2 of the drawings, the inner face 46 of the bottom wall of the work-

arm 2 declines from the partition-wall 20 toward the bearing-supporting lug 13, and said lug is spaced from one side wall of the work-arm to permit lubricant to drain into a reservoir 47 provided at the junction of the carrier-arm 1 and work-arm 2. The feed-forks 40, 43 and the loop-taker shaft driving gearing dip into said reservoir 47.

Depending vertically from the work-arm cover-plate 27 to extend into the reservoir 47, is a filling-tube 48 having at its upper end a shouldered flange 49 tightly fitting an aperture in said cover-plate and provided in its upper face with a recess 50. Removably disposed within the filling-tube 48 is a measuring-gauge in the form of a shouldered rod 51 having a reduced and flattened lower end, and an enlarged shank 51' which slidably fits the bore of said filling tube. The rod-shank 51' terminates at its upper end in a flange 52 seated upon the tube-flange 49 in the recess 50 thereof, the upper end of the rod 51 being formed to provide a knob 53 by means of which the rod may be withdrawn to ascertain the depth of the lubricant within the reservoir 47 and to supply lubricant through the tube 48. The knob 53 is preferably disposed substantially flush with or slightly below the upper face of the cover-plate 27 and the filling-tube 48 is preferably provided, between its ends, with an air-vent aperture 54.

In the operation of the sewing machine, the actuating mechanism disposed within the reservoir 47 acts to agitate the lubricant-supply within said reservoir, thereby lubricating said actuating mechanism and creating a lubricant mist within the work-arm serving to lubricate the feed-bar fulcrum, the connections between the sections of the loop-taker shaft and also the bearing for the shaft-section 9. The partition-wall 20 and the extension 20' thereof, together with the gasketed cover-plate 27 overlying said wall, serve to baffle passage of the lubricant to the free end of the work-arm. The wall 20 is chambered to provide an oil-trap 55 between the wall-slot 34 and the wall-extension slot 35, said oil-trap serving to collect lubricant seeping between the gasket 29 and the feed-bar adjacent the fulcrum-axis of the latter. The lubricant collected in the oil-trap 55 is free to drain back into the work-arm through an aperture 56 provided in the extension-wall 20.

Suitably attached to the under side of the work-arm cover-plate 27 is a U-shaped conduit 57, of which one end terminates adjacent the actuating mechanism within the reservoir 47, whereby lubricant agitated by said mechanism is also supplied to said end of the conduit 57. The conduit 57 declines toward its other end which extends freely through a slot 58 in the partition-wall 20 to terminate in an oil-pocket 59 formed by an upwardly open annular recess in the partition-wall 20. The bottom of the oil-pocket 59 is preferably disposed below the level of the bottom of the slot 58 which opens into said oil-pocket. Therefore, while the slot 58 constitutes an oil-discharge port for excess oil delivered by the conduit 57 to the oil-pocket 59, a residue of oil below the level of the slot 58 will be retained by the oil-pocket and serves as an air-seal for a countersunk aperture 60 in the bottom wall of the oil-pocket 59. The oil-pocket aperture 60 is connected by a duct 61 in the bushing 16 with an annular recess 62 in the shaft-bearing face of said bushing.

Disposed upon the bottom wall of the oil-

5 pocket 59 is an oil-conductor of variable porosity and preferably in the form of a compressible disk 63 of felt or like lubricant-conducting material, and overlying said disk 63 is a circular flange 64 of a screw 65 which is threaded into an apertured boss 66 depending from the under side of the cover-plate 27. The threaded aperture of the boss 66 preferably terminates in the upper face of the cover-plate 27, whereby the slotted upper end of the screw 65 is conveniently accessible. While the flange 64 is diametrically smaller than the oil-pocket 59 and is preferably diametrically smaller than the disk 63, whereby the disk 63 is partly exposed to the oil delivered through the conduit 51, said flange 64 overlies that portion of the disk 63 above and directly adjacent the oil-pocket-aperture 60. By adjustment of the screw 65, the pressure of the flange 64 upon the oil-conducting disk 63 to compress said disk may be regulated to control the delivery of oil by the disk 63 to the bushing recess 62. The oil-metering device described therefore provides for regulating the quantity of oil supplied to the bushing-recess 62, thereby to meet different requirements and more particularly at different speeds of operation of the sewing machine.

10 The loop-taker shaft-section 17 has a longitudinal bore 67 and a diametral aperture 68 connected with one end of said bore within the bushing recess 62. The other end of the shaft-bore 67 is connected in the usual manner by a radial-bore 69 in the loop-taker 22 with the thread-case raceway in said loop-taker.

15 From the foregoing description it will be understood that, in the operation of the machine, lubricant in the reservoir 47 will be splashed into the end of the conduit 57 adjacent the actuating mechanism within said reservoir and that the conduit 57 delivers the lubricant to the oil-pocket 59. The oil-metering device within the oil-pocket 59 provides for regulating the quantity of oil delivered to the loop-taker raceway, the excess lubricant delivered to the oil-pocket 59 draining therefrom into the work-arm 2 through the partition-wall slot 58. The inclined bottom wall 46 of the work-arm 2 drains the excess lubricant into the reservoir 47.

20 It will furthermore be understood that oil seepage along the shaft-bearing face of the bushing 18 provides for lubricating the shaft-section 17. Any lubricant escaping from the end of the bushing 18 provides for lubricating the shaft-section 17. 50 Any lubricant escaping from the end of the bushing 18 provides for lubricating the shaft-section 17. Any lubricant escaping from the end of the bushing 18 provides for lubricating the shaft-section 17. 55 Any lubricant escaping from the end of the bushing 18 provides for lubricating the shaft-section 17. 60 Any lubricant escaping from the end of the bushing 18 provides for lubricating the shaft-section 17. 65 Any lubricant escaping from the end of the bushing 18 provides for lubricating the shaft-section 17. 70 Any lubricant escaping from the end of the bushing 18 provides for lubricating the shaft-section 17. 75

As the radial bore 69 in the loop-taker 22 is longer than the radial length of the loop-taker shaft aperture 68, the centrifugal force developed at the raceway end of the loop-taker bore 69 is greater than the centrifugal force opposing entrance of oil into said shaft-aperture 68. Consequently, the tendency is to develop a suction of oil into the shaft-aperture 68. Owing to the air-seal afforded by the oil-residue in the bottom of the oil-pocket 59, the formation of obstructing air-bubbles in the oil-conducting connections between said pocket and the loop-taker raceway is eliminated, it being understood that the continuous delivery of oil to the oil-pocket 59 during the operation of the machine, together with the oil-metering device described, not only insures a constant oil-residue in said oil-pocket 59, but also

provides for efficient and regulatable lubrication of the loop-taker raceway.

Having thus set forth the nature of the invention, what I claim herein is:

1. A sewing machine having a rotary loop-taker provided with a thread-case raceway and with a radial bore connected with said raceway, a rotary loop-taker carrying shaft provided with a longitudinal bore connected with said radial bore of the loop-taker, said shaft having a radial aperture connected with said shaft bore and substantially shorter than the length of the loop-taker bore, an oil-pocket having a bottom-wall aperture connected with the radial aperture of said shaft, said oil-pocket having an excess-oil discharging port above the level of said bottom-wall aperture whereby an air-sealing residue of oil is disposed in said pocket, means for controlling the flow of oil through the bottom-wall aperture of said pocket, and means effective during the operation of the machine for supplying oil to said pocket.

2. A sewing machine having a rotary loop-taker provided with a thread-case raceway, a rotary loop-taker carrying shaft provided with a longitudinal bore having lubricant-conducting connections with said raceway, an oil-pocket having an aperture connected with the bore of said shaft, said oil-pocket having an excess-oil discharging port above the level of said aperture, an oil-conductor of variable porosity disposed in said oil-pocket to overlie said aperture, means for supplying lubricant to said oil-pocket, and manually adjustable means for regulating the porosity of said oil-conductor.

3. A sewing machine having a frame including a hollow work-arm internally provided with a transverse partition-wall rising from the bottom wall and extending from one to the other side wall of said work-arm, said partition-wall being provided lengthwise of said work-arm with a shaft-bearing aperture and with a slot enlarged between the ends thereof to provide an oil-trap in said partition-wall, a rotary loop-taker shaft journaled in said bearing-aperture, a loop-taker carried by said shaft at one side of said partition-wall, a feed-bar extending through and slidably disposed in said partition-wall slot, a feed-dog carried by said feed-bar at the loop-taker side of said partition-wall, a lubricant-reservoir in said frame at the opposite side of said partition-wall, and mechanism including a member dipping into said reservoir for rotating said loop-taker shaft and for actuating said feed-bar to impart work-feeding movements to said feed-dog lengthwise of said work-arm.

4. A sewing machine having a rotary loop-taker provided with a thread-case raceway, a lubricant-supply reservoir, a lubricant-pocket disposed between said reservoir and said raceway and provided with excess-lubricant discharge means, a lubricant-metering device disposed in said lubricant-pocket below the level of said discharge means, means for supplying a flood of lubricant from said reservoir to said lubricant-pocket, and suction-inducing means for drawing lubricant through said metering device and delivering it to said raceway.

5. A sewing machine having a rotary loop-taker provided with a thread-case raceway, a lubricant-supply reservoir, a lubricant-pocket disposed between said reservoir and said raceway and provided with excess-lubricant discharge means, a lubricant-metering device disposed in said lubricant-pocket below the level of

said discharge means, means for supplying a flood of lubricant from said reservoir to said lubricant-pocket, suction-inducing means for drawing lubricant through said metering device and delivering it to said raceway, and means for conducting away from said lubricant-pocket an excess of lubricant delivered to said metering device.

6. A sewing machine having a rotary loop-taker provided with a thread-case raceway, a lubricant-supply reservoir, a lubricant-pocket disposed between said reservoir and said raceway and provided with excess-lubricant discharge means, a lubricant-metering device disposed in said lubricant-pocket below the level of said discharge means, means including an element operated by a moving part of the machine for supplying a flood of lubricant from said reservoir to said metering device, suction-inducing means for drawing lubricant through said metering device and delivering it to said raceway, and means for conducting away from said lubricant-pocket an excess of lubricant delivered to said metering device.

7. A sewing machine having a rotary loop-taker provided with a thread-case raceway, a lubricant-supply reservoir, a lubricant-pocket disposed between said reservoir and said raceway and provided with excess-lubricant discharge means, a lubricant-metering device disposed in said lubricant-pocket below the level of said discharge means, means including an element operated by a moving part of the machine for supplying an excess of lubricant to said metering device from said reservoir, suction-inducing means for drawing lubricant through said metering device and delivering it to said raceway, and means for returning to said reservoir excess-lubricant delivered to said metering device.

8. A sewing machine having a rotary loop-taker provided with a thread-case raceway and with a radial duct connected with said raceway, a rotary loop-taker carrying shaft provided with a longitudinal bore connected with said radial duct of the loop-taker, said shaft having a radial aperture connected with said shaft bore and substantially shorter than the length of the loop-taker duct, a lubricant-supply reservoir, a lubricant-pocket disposed between said reservoir and said radial duct of the loop-taker shaft, said pocket being provided with excess-lubricant discharge means, a lubricant-metering device disposed in said lubricant-pocket below the level of said discharge means, means rendered effective by a moving part of the machine for delivering lubricant from said reservoir to said metering device, means for conducting lubricant delivered by said metering device to the radial duct of said loop-taker shaft, manually adjustable means for regulating the lubricant-delivering capacity of said metering-device, and means for returning to said reservoir excess-lubricant discharged from said pocket.

9. A sewing machine having a work-support, a rotary loop-taker disposed below said work-support and provided with a thread-case raceway, a lubricant-supply reservoir, a lubricant-pocket disposed below said work-support and provided

with excess lubricant discharge means, a compressible lubricant-penetrant metering element disposed in said lubricant-pocket below the level of said discharge means, means for supplying lubricant from said reservoir to said metering element, suction-inducing means for drawing lubricant through said metering element and delivering it to said raceway, and manually adjustable means accessible from above said work-support for regulating the degree of compression of said metering element.

10. A sewing machine having a work-support, a rotary loop-taker disposed below said work-support and provided with a thread-case raceway, a lubricant-supply reservoir, a lubricant-pocket disposed below said work-support and having lubricant-conducting connections with said raceway, a compressible lubricant-penetrant metering element disposed in said lubricant-pocket, a metering-element regulating screw threaded into said work-support, said screw having a flanged lower end in engagement with said metering element and having its upper end accessible from above said work-support, and means including an element operated by a moving part of the machine for supplying lubricant from said reservoir to said pocket.

11. In a sewing machine having a frame including a hollow work-arm free at one end thereof, a rotary loop-taker disposed within said work-arm at the free end thereof and having a thread-case raceway, a rotary loop-taker carrying shaft provided with a longitudinal bore terminating at one end in a radial shaft-aperture and having lubricant-conducting connections at its other end with said raceway, a lubricant-reservoir within the end portion of said work-arm opposite to the free end thereof, a lubricant-pocket disposed within said work-arm having excess lubricant-discharge means and having lubricant-conducting connections with said radial shaft-aperture, a manually regulatable lubricant-metering device in said pocket below the level of said discharge means, a lubricant-conduit extending lengthwise of said work-arm disposed to discharge a flood of lubricant in said pocket, and mechanism adapted to dip into lubricant in said reservoir for supplying lubricant to said conduit.

12. In a sewing machine having a frame including a hollow work-arm free at one end thereof, a cover-plate detachably secured upon said work-arm, a rotary loop-taker disposed within said work-arm at the free end thereof and having a thread-case raceway, a rotary loop-taker carrying shaft provided with a longitudinal bore connected with said raceway, said shaft having a radial inlet-aperture connected with said bore, a lubricant reservoir in said frame at the end of said work-arm opposite to the free end thereof, a lubricant conduit attached to the under side of said cover-plate for removal therewith and extending lengthwise of said work-arm, said conduit having lubricant-conducting connections with said inlet-aperture of the loop-taker shaft, and means for supplying lubricant from said reservoir to said conduit.

WALTER MYERS.
